UNITED STATES PATENT OFFICE.

EUGENE R. DURKEE, OF BROOKLYN, NEW YORK.

DESIGN FOR BOTTLE.

Specification forming part of Design No. 7,988, dated January 5, 1875; application filed December 28, 1874.
[Term of Patent 3½ years.]

To all whom it may concern:

Be it known that I, EUGENE R. DURKEE, of Brooklyn, in the county of Kings and State of New York, have invented a Design for a "Chilli-Sauce" (or other spice or sauce) Bottle, of which the following is a specification:

The nature of my design is fully represented in the accompanying photographic illustration, to which reference is made.

A represents a hexagonal bottle, (though it may be made of any other number of angular sides desired,) having its end for about one-third the length of the body of the bottle converged, so as to form the rounded neck B, and terminates in two raised beads, C, encircling the neck. The sides D of the bottle are flat, and terminate at their upper ends in a lance-point, E. Around the panels or flat surfaces,

on all sides, is formed a raised bead, F, like the setting of a Gothic door, thus giving relief to the panels and the labels that may be pasted thereon.

Having now described my new design of a sauce-bottle, I will proceed to set forth what I claim and desire to secure by Letters Patent of the United States.

I claim as my invention—

The design for a sauce-bottle in which the sides are formed in flat panels with lance-points, and surrounded with a raised bead, substantially in the manner hereinbefore set forth.

EUGENE R. DURKEE.
